UNITED STATES PATENT OFFICE.

LARKIN H. BROWN AND GEORGE E. REPASS, OF KNOXVILLE, TENNESSEE, ASSIGNORS
TO DRAPER CORPORATION, OF HOPEDALE, MASSACHUSETTS, A CORPORATION OF
MAINE.

FEELER MECHANISM FOR LOOMS.

Application filed March 26, 1925. Serial No. 18,548.

This invention relates to feeler mechanisms which are applied to automatic looms for causing the automatic replenishing mechanism to function when the filling on the bobbin in the shuttle has become nearly exhausted.

In the form shown in the accompanying drawings, the feeler is a right hand side swipe or slipping feeler. It is to be understood that the mechanism may be reversed for left hand side swipe or slipping.

The object of the invention is to produce such a mechanism in simple form, comprising a small number of parts and adapted to accurate and long continued performance without needing adjustment or repairing, whereby the feeler mechanism and the replenishing mechanism may be adjusted for discharge of the bobbin from the shuttle with the smallest feasible quantity of yarn remaining on the bobbin as wastage, and whereby loss of time by stopping the loom is reduced.

A further object is to produce a feeler mechanism in a form to avoid accidents to the fingers and hands of operatives.

Reducing the quantity of yarn left on the bobbin when the transfer is made is a financially important matter. Under present weaving practice, this wastage is relatively so large as to make, in the aggregate, a large loss item in the operation of a mill. In some lines of work this wastage is as much as two per cent of the yarn. That means two tons of wastage out of one hundred tons of yarn. As wastage, this material is sold at a large loss per pound. Two tons of yarn are an important item.

By making the feeler action sensitive and accurate and durable, it is safe to so wind the bobbins as to provide for sliding of the feeler when the yarn on the bobbin is only sufficient to constitute a safe reserve length of yarn until the bobbin has been discharged.

In the accompanying drawings,

Fig. 1 is a perspective view of a feeler mechanism containing the present invention;

Fig. 2 is a plan of the supporting body, the cover of said body having been removed to show the feeler and associated members, those parts being at rest with the feeler

in its outer and left hand or feeling position, perpendicular to the bobbin axis;

55

Fig. 3 is a view of the same mechanism with the feeler pushed endwise without side- wise movement;

Fig. 4 shows the same mechanism with the feeler moved toward the right by contact with the nearly empty bobbin;

Fig. 5 is a plan of the oscillating feeler carriage, the cover of the carriage having been turned to fully expose the feeler;

Fig. 6 is a section on the line, 6—6, of Fig. 5, looking in the direction of the arrows;

Fig. 7 is a section on the line, 7—7, of Fig. 2, the body cover being in position;

Fig. 8 is an upright section on the line, 8—8, of Fig. 2, looking in the direction of the arrow, the body cover being in position;

Fig. 9 is an upright section on the line, 9—9, of Fig. 1, looking in the direction of the arrows;

Fig. 10 is an upright section on the line, 10—10, of Fig. 1, looking in the direction of the arrows, the slide bolt being in the inactive or retracted position;

Fig. 11 is an upright section on the line, 11—11, of Fig. 1, looking in the direction of the arrows, the cam follower hook being in engagement with the slide bolt;

Fig. 12 is a horizontal section on the line, 12—12, of Fig. 11.

Referring to said drawings, A is the body of the feeler mechanism. Said body is horizontal and oval as viewed in plan. A¹ is the cover for said body. A² is an upright bracket supporting said body. Said bracket has a flat horizontal head, A³, on which rests the bottom of the body, A. Cap screws, A⁴, extend upward through said head into the body, A, to rigidly secure the body to the head. The bracket, A², is suitably secured to a stationary part, A⁵, of the loom by means of a bolt, A⁶. An upright circumferential main wall, A⁷, rises from the bottom or floor of the body, A, and makes said body dish-form. But said wall is cut low at a part of the body to make room for the feeler carriage. Enough of this wall is left to make a dam or retaining member, A⁸, which prevents the outward flow of lubricant lying on the bottom of said body.

90

95

100

105

Near the middle of the body, A, an up-

- right stationary pivot post or first fulcrum, A⁹, rises from the bottom of the body. Said post extends into the bearing, C¹, of the 5 feeler carriage, C. That bearing is in a leftward extension, C², on the end of said carriage. The carriage is adapted to oscillate on said post in a horizontal plane and that is the only movement allowed said carriage.
- 10 The feeler carriage has a flat cover, C³, which is pivoted on the upright headed post, C⁴, which is seated in the rightward extension, C⁵, at the outer or forward end of the carriage. Normally the pivot post, A⁹, extends upward through the carriage body and the cover, C³, and prevents turning of the cover on the post, C⁴. Normally the cover, A¹, of the body, A, extends across the carriage, C, and holds it against rising.
- 15 Thus the carriage and its cover, C³, are held in position on the pivot post, A⁹. When the cover, A¹, has been removed and the carriage, C, has been lifted out of engagement with the pivot post, A⁹, the carriage cover, C³, may be turned sidewise with the post, C⁴, acting as a journal.
- 20 The upper part of the carriage below the cover, C³, is channeled lengthwise to receive the main part of the flat or blade-form 30 feeler, D, the fit of the feeler in the channel being sufficiently loose to allow easy endwise sliding of the feeler in the channel. Between the feeler, D, and the bearing, C¹, of the carriage there is formed in the carriage a circular oil recess, C⁷, in which is placed a filling of felt or similar 35 absorbent material. Said recess is made large enough to communicate with the bearing, C¹, and the channel of the carriage, in order that lubricating oil put into the recess may pass from said recess into said bearing and into said channel. An oil port, C⁸, extends downward from the recess, C⁷, through the extension, C², to permit oil to 40 pass downward from the recess, C⁷, to the bottom of the body, A. Above the recess, C⁷, an oil port, A¹⁰, is formed in the cover, A¹, and an oil port, C⁶, is formed in the carriage cover, C³. The nozzle of an oil can 45 may pass oil through the ports, A¹⁰ and C⁶, into the recess, C⁷. The bearing, C¹, also extends through the carriage cover, C³. The dam, A⁸, prevents the outward flow of oil lying on the bottom of the body, A. Thus 50 provision is made for lubricating all the moving members of this part of the mechanism. This includes the lubrication of the ends of the spring, D⁴, to be described.
- 55 The feeler D has an arm or extension D¹, which, as shown, projects laterally from the feeler and inclines rearwardly. The end portion of the laterally extending arm may be provided with a shoulder D², adapted to engage the abutment or second fulcrum A¹¹ 60 formed as part or secured to the body or

feeler stand A. The laterally extending arm D¹ is normally under the influence of a spring tending to move the feeler into its rearward feeling position, and, while the details in these respects may be variously contrived, the arm D¹ is here shown as provided with a post D³ which receives one end of the contractile spring D⁴, the other end of which is secured to a post A¹² at the rear portion of the body or feeler stand, the construction being such that the spring tends to move the feeler rearwardly, thereby causing the end or shoulder D² of the arm D¹ to engage the stop or abutment A¹¹ and effect swinging movement of the carriage C to the left, as shown, and into engagement with a limiting stop or abutment A¹³.

75 When not engaged by the bobbin or the filling on the bobbin, the action of the spring, D⁴, holds the feeler carriage in its leftward position against the abutment, A¹³, and holds the feeler in its farthest rearward position in the carriage, the shoulder, D², of the feeler at such times resting against the abutment, A¹¹, which serves as a fulcrum 80 or pivot.

85 When the feeler engages a working supply of filling in the shuttle on a detecting beat, the feeler is moved frontwardly by the frontward pressure upon it, while the rear toothed end of the feeler sinks into the filling to prevent side slipping movement thereof. As the feeler moves frontwardly, the spring D⁴ connected to the laterally extending arm D¹ of the feeler is placed under 90 greater tension and as the lay goes back the feeler will be moved rearwardly in the feeler carriage until it again assumes the position indicated in Fig. 2 with the end or shoulder D² of the laterally extending arm D¹ engaged with the abutment A¹¹, whereupon the feeler and its carriage are moved to bring the latter into engagement with the stop A¹³.

100 As already stated, the spring, D⁴, tends to move the feeler, D, leftward when the feeler is in its rearward position and the shoulder, D², rests against the abutment, A¹¹. Under that condition, the point of contact between that shoulder and that abutment 105 is the pivotal point for the turning of the feeler. But when the feeler is pushed frontwardly whereby the shoulder is moved out of contact with that abutment, the pivot post, A⁹, becomes the axis or fulcrum on

110 which the spring tends to turn the feeler. Then the force of the spring is exerted to throw the rearward part of the feeler rightward—in the direction to throw the transfer mechanism into action. Furthermore, as indicated by the line, a—a, on Fig. 2 of the drawings, the rearward or free end of the feeler is at the right of the axis formed by the pivot post, A⁹, so that pressure frontward 115 against the rear end of the feeler will tend

120 to move the feeler rearwardly. The shoulder, D², is at the left of the axis formed by the pivot post, A⁹, so that pressure frontward against the shoulder will tend 125 to move the feeler forwardly. The shoulder, D², is at the right of the axis formed by the pivot post, A⁹, so that pressure frontward against the shoulder will tend 130 to move the feeler forwardly.

to turn the feeler and the feeler carriage toward the right. Hence when the nearly empty bobbin is pressed against the rear end of the feeler, such pressure tends to cause 5 and causes the feeler to slip sidewise, toward the right, on the face of the bobbin, the feeler carriage being turned rightward with the feeler. From the foregoing it will be seen that this action of the bobbin tending 10 to move the feeler rightward and the action of the spring, D⁴, to move the feeler rightward are combined. And it is to be noted that the spring acts on the line, b—b, and that line passes between the two fulcra, the 15 pivot post, A⁹, and the abutment, A¹¹.

As soon as the nearly empty bobbin retreats, its pressure on the feeler ceases, and the spring at once draws the feeler rearward through the carriage until the shoulder, 20 D², again makes contact with the abutment, A¹¹, whereupon that point again becomes the fulcrum for turning the feeler and the feeler carriage toward the left until the carriage bears against the abutment, A¹³, the 25 carriage and the feeler then being in their rest positions.

The rightward movement of the rear end of the feeler carriage moves the connecting rod, E, endwise toward the right. The 30 left hand end of said rod is bent downward and extended into an eye, C¹⁰, formed on the rear part of the right hand edge of the feeler carriage, C, adjacent the hinge post, C⁴, on which the feeler carriage cover, C³, 35 may turn, as already described. The cover, A¹, of the feeler body, A, has an extension, A¹⁴, which reaches over the adjacent part of the connecting rod and prevents said rod from rising and disengaging itself from the 40 feeler carriage.

F is an approximately horizontal actuator of well known form and suitably supported for endwise movement and operatively connected with the bobbin transfer mechanism 45 (not shown). On the rearward end of the actuator is a head, F¹, which has a channel, F², parallel to the length of the actuator and opening downward. On the left hand side of said head is a sleeve or bearing, F³, opening into said channel. Said bearing is horizontal and perpendicular to the length of the actuator. In the face of the actuator head on the side of the channel opposite the bearing, F³, and in axial alignment with 50 said bearing is a socket, F⁴, of the same diameter as the interior diameter of said bearing. The interior of said bearing and said socket are preferably cylindrical. A cylindrical, rotatable slide bolt, E⁸, lies in said bearing and is adapted to be moved rightward across the channel, F², and into the socket, F⁴. In alignment with said slide bolt is a connecting block, E¹, on the right hand end of which is a ball, E², resting in a 55 socket, E⁴, formed on the adjacent end of the 60

slide bolt. Thus a universal joint is formed between the slide bolt and the connecting block. The left hand end of the connecting block is hollow and interiorly screw-threaded to receive the adjacent exteriorly screw-threaded end of the connecting rod, E. At the left of the connecting block, E¹, a jam nut, E⁵, is threaded around the connecting rod, E. When the jam nut has been loosened, the connecting rod and the coupling 70 block may be relatively turned to shift said block endwise on the connecting rod for varying the distance between the right hand end of the slide bolt and the feeler carriage. 75

For its endwise movement, the actuator is dependent upon action by the cam follower, G, which is positioned and actuated periodically (by any well-known means not shown) to move forward into the channel, F², of the actuator. But the cam follower makes no engagement with the actuator unless the slide bolt, E⁸, is in its rightward position and extending across the channel, F², and forms an abutment against which the 80 hook of the cam follower bears. The part, E⁵, of the slide bolt which extends across the channel, F², is tapered, leftward across said channel. The face of the cam follower hook which engages said part, E⁵, of the 85 slide bolt is correspondingly slanted. Thus tendency toward leftward movement of the slide bolt when the bolt is engaged by the hook is avoided. On the contrary, this engagement is such as to tend to hold the 90 slide bolt in its right hand or working position.

Extending the slide bolt into the socket, F⁴, gives said bolt greater stability when it 100 is engaged by the cam follower hook. 105

When the block, E¹, is to be adjusted on the connecting rod, the ball and socket joint between the coupling block, E¹, and the slide bolt, E⁸, allows the turning of the block, E¹, on the connecting 110 rod, E, without detaching said rod or removing the slide block, E⁸. Furthermore, said ball and socket joint and the upright coupling at the left hand end of the connecting rod form two joints permitting 115 free movement during the endwise movements of the actuator, F. These joints and the manner of supporting the slide bolt provide for easy endwise movement of the connecting rod, the coupling block, and the slide bolt. Such easy movement is desirable 120 during the rightward movement and also during the leftward movement of the feeler carriage, C. During those movements, the feeler carriage causes the endwise movement of the connecting rod, the coupling block, and the slide bolt. These members should offer the least resistance to such movements, in order to limit the work to be done by the 125 spring, D⁴. To give the mechanism long 130

continued accurate action, the spring must be given a load which is as light as is feasible.

It has already been explained how the parts directly associated with the body, A, are arranged and lubricated for easy movement. The slide bolt is formed for easy movement in the bearing, F³, and said bearing has an upper oil port, F⁴, for the introduction of oil to facilitate sliding of the slide bolt.

It will now be observed that all the parts of this mechanism are adapted to economical manufacture and to easy assembling and adjustment and separation. When the cover, A¹, has been removed from the body, A, the spring, D⁴, may be detached from the posts, D³ and A¹², and a new spring substituted, if such substitution is necessary. To limit wear, those posts are made of copper or similar soft metal. After the spring, D⁴, has been detached, the feeler carriage may be lifted out of engagement with the post. Then the carriage cover, C³, may be turned on the hinge post, C⁴, into the position shown by Fig. 5. Then the feeler, D, may be lifted out of the carriage and repaired or replaced by another feeler. Here it is to be remembered that when the carriage is in its working position, the pivot post, A⁹, extends into the carriage cover and prevents it from turning on the hinge post, C⁴. After the cover, A¹, has been removed, the adjacent end of the connecting rod may be lifted out of engagement with the carriage.

Attention is especially invited to the fact that the body, A, and the cover, A¹, enclose the main part of the feeler and the feeler carriage and the spring. Thus these parts and the lubricant within the body are kept free from dirt and lint. This keeps these parts in condition for easy and quick movement, a condition necessary for prolonged and accurate and reliable service.

Furthermore, this construction has an important bearing upon safety for operatives. In forms of feeler mechanisms now in use on looms, the working parts are so exposed as to often cause the pinching of the hands or fingers of the operatives, the mechanisms being so located as to permit accidental bringing of the hand or fingers into engagement while the attention of the operative is directed elsewhere. Hands of operatives injured in this way frequently require treatment. In our improved mechanism, the body, A, and the cover, A¹, render the mechanism safe in this respect. The hand of the operative may rest on this part of the mechanism without injury.

We claim as our invention:

1. In a feeler mechanism for looms, the combination of a stationary body providing a first and a second fulcrum or turning

point, a carriage placed horizontally on said body and perpendicularly to the bobbin axis and pivoted on the first fulcrum, the two fulcrums being at the same side of the longitudinal axis of the carriage, a feeler supported by the carriage for endwise sliding on the carriage and having a lateral extension normally reaching to the second fulcrum, and a spring engaging said extension between the two fulcrums, substantially as described.

2. In a feeler mechanism for looms, the combination of a feeler carriage mounted for swinging movement about a first fulcrum at one side of its central longitudinal axis, a feeler mounted on the carriage for lengthwise movement relative thereto and swinging movement therewith and having a lateral extension, a fulcrum stop adapted for engagement by said extension, and a spring acting upon the extension between the two fulcrums and normally tending to move the feeler rearwardly and to swing the feeler and carriage about the first fulcrum when the filling is substantially exhausted on a detecting beat.

3. In a feeler mechanism for looms, the combination of a stationary body providing a first and a second fulcrum or turning point and an abutment for limiting the sidewise movement of the feeler in the direction of rest, a carriage placed horizontally on said body and perpendicularly to the bobbin axis and pivoted on the first fulcrum, the two fulcrums being at the same side of the longitudinal axis of the carriage, a feeler supported by the carriage for endwise sliding on the carriage and having a lateral extension normally reaching to the second fulcrum, and a spring engaging said extension between the two fulcrums, substantially as described.

4. In a feeler mechanism for looms, the combination of a feeler carriage mounted for swinging movement about a first fulcrum at one side of its central longitudinal axis, a feeler mounted on the carriage for lengthwise movement relative thereto and swinging movement therewith and having a lateral extension, a fulcrum stop adapted for engagement by said extension, and a spring acting upon the extension between the two fulcrums and normally tending to move the feeler rearwardly and to swing the feeler and carriage about the first fulcrum when the filling is substantially exhausted on a detecting beat and an abutment for limiting the sidewise movement of the feeler in the direction of rest.

5. In a feeler mechanism for looms, the combination of a feeler carriage mounted for swinging movement about a fulcrum at one side of its central longitudinal axis, a feeler mounted for lengthwise movement on the carriage and having a lateral extension

frontward of the feeler carriage, a fulcrum stop adapted to be engaged by said lateral extension, and a spring acting upon the extension between the two fulcras and normally tending to move the feeler rearwardly on the carriage.

6. In a feeler mechanism for looms, the combination of a feeler carriage pivotally supported at one side of its central longitudinal axis, a feeler mounted on the carriage for lengthwise movement and having a lateral extension, a spring acting on the lateral extension and normally tending to move the feeler rearwardly on the feeler carriage, a fulcrum stop at the same side of the central longitudinal axis of the carriage as the pivotal support and adapted to be engaged by the lateral extension of the feeler under the impulse of said spring to move the feeler and feeler carriage into a position substantially at right angles to the longitudinal axis of the shuttle.

7. In a feeler mechanism for looms, the combination of a stationary body having a cover and providing a first and a second fulcrum or turning point, a carriage placed horizontally on said body and perpendicularly to the bobbin axis and pivoted on the first fulcrum, the two fulcras being at the same side of the longitudinal axis of the carriage, a feeler supported by the carriage for endwise sliding on the carriage and having a lateral extension normally reaching to the second fulcrum, and a spring engaging said extension between the two fulcras, substantially as described.

8. In a feeler mechanism for looms, the combination of a stationary body or feeler stand, a feeler carriage mounted for swinging movement about a fulcrum at one side of its central longitudinal axis, a feeler mounted for lengthwise movement on the feeler carriage and having a lateral extension projecting to one side of its longitudinal axis, a fulcrum stop adapted to be engaged by said lateral projection and a pull spring acting to move the feeler rearwardly on the feeler carriage.

9. In a feeler mechanism for looms, the combination of a body or feeler stand, a feeler carriage mounted for swinging movement about a fulcrum at one side of its central longitudinal axis, a feeler mounted on the carriage for lengthwise movement relative thereto and having a laterally extending arm, a fulcrum stop adapted for engagement by said laterally extending arm, and a spring normally tending to move the feeler rearwardly to effect engagement of said arm with the fulcrum stop and to swing the feeler carriage about its fulcrum, and a stop for limiting the swinging movement of the carriage under the impulse of said spring.

10. In a feeler mechanism for looms, the

combination with a body having a pivot post, of a feeler carriage channeled lengthwise and having a lateral extension in which is a bearing receiving said pivot post and said extension having a lubricant recess communicating with said bearing and with said channel and having in its lower part a port communicating with said body, and a feeler resting slidably in the carriage channel, substantially as described.

11. In a feeler mechanism for looms, the combination with a body having a circumferential upright wall, a portion of which wall is cut away leaving a low part at the bottom to form a dam and said body having a pivot post, of a feeler carriage channeled lengthwise and having a lateral extension in which is a bearing receiving said pivot post and said carriage extending outward across the low part of said wall, a feeler resting slidably in said channel, and a spring associated with said feeler, substantially as described.

12. In a feeler mechanism for looms, the combination with a body having a circumferential upright wall, a portion of which wall is cut away leaving a low part at the bottom to form a dam and said body having a pivot post, of a feeler carriage channeled lengthwise and having a lateral extension in which is a bearing receiving said pivot post and said carriage extending outward across the low part of said wall and the carriage having a lubricant recess in the lower part of which is a port, a feeler resting slidably in said channel, and a spring associated with said feeler, substantially as described.

13. In a feeler mechanism for looms, the combination of a relatively stationary body, a carriage pivoted to said body at one side of the longitudinal axis of said carriage and having near its free end a lateral extension in which is a bearing, a feeler slidably supported on said carriage, a spring engaging said feeler, an actuator on which is a bearing, a rotatable slide bolt in said bearing, and a connecting rod having a downward extension resting in said bearing and said rod being in operative relation with said slide bolt, substantially as described.

14. In a feeler mechanism for looms, the combination of a relatively stationary body, a carriage pivoted to said body, a feeler slidably supported on said carriage, a spring engaging said feeler, an actuator channeled and having a bearing on one side of the channel, a slide bolt resting in said bearing and adapted to extend across said channel, the part of said bolt which is to extend across the channel being tapered, connecting means extending from the carriage to the slide bolt, and a follower member having its contact face made slanting, substantially as described.

15. In a feeler mechanism for looms, the combination of a carriage having a pivotal mounting offset from its longitudinal axis, a feeler slidable endwise on said carriage, and a spring in operative relation with the feeler to tend to move the feeler and the carriage to the rest position when the feeler is free from the bobbin and to move the feeler and the carriage in the reverse direction when the feeler is pressed endwise by the bobbin or the filling on the bobbin, substantially as described.
16. In a feeler mechanism for looms, the combination of a stationary body providing a first fulcrum and a second fulcrum, a carriage engaged on the first fulcrum laterally at one side of its longitudinal axis, a feeler endwise slidable on the carriage, a spring in operative relation with the feeler to normally directly act on the second fulcrum and indirectly on the first fulcrum to turn the carriage and the feeler to the rest position when the feeler is free from the bobbin and to act directly through the second fulcrum to turn the carriage and the feeler in the opposite direction when the feeler is pressed endwise by the bobbin, substantially as described.
17. In a feeler mechanism for looms, the combination of a stationary body, a channeled carriage, a unitary blade-form feeler supported on the carriage for endwise slid-
- ing and having its rear end folded to form a lateral extension, and a spring engaging said lateral extension, substantially as described.
18. In a feeler mechanism for looms, the combination of a stationary body or stand, a feeler carriage pivotally mounted on the stand, a feeler mounted for longitudinal sliding movement on the carriage and having a lateral extension, a fulcrum stop adapted to be engaged by said extension, and a spring having one end secured to the stand rearward of the lateral extension and its outer end secured to the lateral extension between the feeler and the terminal portion of the lateral extension.
19. In a feeler mechanism for looms, the combination with a stationary body on which is a pivot post, of a carriage comprising a channeled body and a cover hinged to said body and said carriage body and said cover being apertured to receive the pivot post whereby the carriage body is pivoted and that part of the cover is secured on the carriage body, and a feeler lying in the channel of the carriage body, substantially as described.

In testimony whereof we have signed our names, in the year one thousand nine hundred and twenty-five.

LARKIN H. BROWN.
